[57] CLAIM

The ornamental design for an outer surface of element
for lighting fixture, as shown and described.

DESCRIPTION

FIG. 1 is a front view in elevation of an outer surface of
an element for a lighting fixture showing my new de-
sign;

FIG. 2 is a right side view thereof, the left side being a
mirror image thereof;

FIG. 3 is a top plan view thereof; and,

FIG. 4 is a bottom plan view thereof.

The broken lines shown in the drawings are environ-
mental only and form no part of the claimed design.
